MARKING MACHINE

William S. Petty, Denver, Colo., assignor to Russell Young and William Young, both of Denver, Colo.

Application February 4, 1937, Serial No. 124,052

13 Claims.

(Cl. 101—97)

This invention relates to a marking machine, more particularly of the type for placing identification marks upon laundry and has for its principal object the provision of a rapid, simple, light-weight, highly efficient machine which can be used by anyone without damage to the goods or the operator.

Another object of the invention is to eliminate the large number of complicated parts usually employed in a machine of this character and to enclose all of the type wheel operating mechanism within the type wheels themselves so that an enclosing cabinet or case will not be necessary.

A further object is to provide a highly efficient inking mechanism for the type wheels which can be quickly and easily reached for the re-inking and which will not interfere with the goods being marked or the operation of the machine.

Other objects and advantages reside in the detailed construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a left side elevation of the improved machine.

Fig. 2 is a similar view illustrating the work mandrel in the closed position.

Fig. 3 is a detail view of the inking pad in the type engaging position.

Fig. 4 is a sectional view through the inking pad with the latter in re-inking position.

Fig. 5 is a plan view of the complete machine.

Fig. 6 is a detail side view of a typical type wheel with the cover plate removed.

Fig. 7 is a detail rear face view of one of the drive gears.

Fig. 8 is a detail horizontal section, taken on the line 8—8, Fig. 9.

Fig. 9 is a vertical section taken on the line 9—9, Fig. 8.

Fig. 10 is a left side elevation of the machine.

Fig. 11 is a front view of the machine.

Fig. 12 is a detail section through the pawl housing.

Fig. 13 is a detail section through the pawl housing taken on the line 13—13, Fig. 12.

The improved machine employs a base 10 from which two A-shaped standards 11 and 12 extend upwardly to support a series of annular type

wheels 13 provided with type characters 16, with which the actual marking is accomplished. The standards 11 and 12 terminate in circular disc-like upper extremities which form cover plates for the open interior of the type wheels.

A third standard 59 is spaced from, and extends above, the type wheels 13 to support an index sector 14 carrying an index 15 of the characters carried by the type wheels 14, such as the alphabet and the numbers from one to zero.

Each of the type wheels 13 is provided with internal gear teeth 17, and each is rotated by a countergear 18 having corresponding teeth in mesh therewith. It is preferred to have the internal gear teeth 17 correspond in number to the characters 16. The counter-gears 18 ride upon a counter-shaft 19 supported between the cover plate portions of the standards. Each of the counter-gears 18 is formed with a concentric driven pinion 20 thereon, and each of the driven pinions 20 is driven from an independent drive gear 21.

The drive gears 21 are rotatable upon a hollow shaft 22 which is journaled in the standards 11, 12, and 59 and terminates in a fixed gear 60 at the standard 59. The fixed gear and the hollow shaft 22 can be rotated by means of a setting lever 23 which is pivoted on the standard 59 and carries a gear segment 61 in mesh with the fixed gear 60. Normally the shaft 22 can rotate freely within the drive gears 21. The gears, however, are selectively rotated from the shaft 22 by means of a key 24 which extends through a longitudinal slot in the hollow shaft 22 from a slidably control bar 25 within the shaft.

Each of the driven gears 21 is formed with a passage 26 for the passage of the key 24. The back of each gear is formed with a pear-shaped boss 62 having an annular chamber 63, for the reception of the key 24, which terminates in a stop tongue 64 against which the key strikes to rotate the gear. Thus, if the key 24 is within the chamber of the first gear 21 it will contact the stop 64 therein to rotate the first type wheel. The remaining type wheels do not move since the key 24 can be in but one of the wheel chambers 63 at a time. It travels from gear to gear through the passages 26, into successive engagement with the gears 21 due to longitudinal movement of the control bar 25.

The control bar is formed with a rack of ratchet teeth 27 which are successively engaged by a toothed pawl 28. The pawl 28 contacts with a fixed cam 29 at the completion of each downward stroke of the lever 23. This contact forces

the pawl 28 to the right, and it in turn, through the ratchet teeth 27 pulls the core 25 to the right so as to bring the key 24 within the next successive drive gear. A check pawl 38, mounted alongside the pawl 28, clicks over the rack teeth to prevent return of the bar 25.

The type characters on the various type wheels 18 are aligned with each other by means of a series of individual click members 36 which are forced between the teeth of the counter gears 18 by means of click springs 31 to cause the counter gears to always stop at their tooth positions, thus aligning the type characters 18 in predetermined lines across the type wheels.

15 After the printing has been completed all of the type wheels are returned to their former positions by means of a resetting bar 32 which is mounted on a rotatable sleeve 37 on the hollow shaft 22. The sleeve 37 carries a small pinion 38 which is driven from a segment gear 34 journaled on a resetting shaft 36. The segment gear 34 is secured to, and rotated by, a resetting lever 35 which projects above the type wheels as illustrated. The resetting bar 32 travels 20 around the gears 21 and contacts a series of resetting teeth 33, one of which projects from the pear-shaped boss 52 on each of the gears 21. A stationary aligning stud 58 stops all of the resetting teeth 33 at the "zero" or starting position.

25 A compression spring 37 constantly urges the bar 32 to the starting position against the action of the pawls 28 and 38 and naturally if these pawls are lifted out of engagement with the teeth 27, this spring will snap the bar 32 back to its starting position within the first type wheel. The lifting of the pawls is accomplished by means of a resetting cam 38 which is secured 30 on the segment gear 34 so as to move with the resetting lever 35. This cam is formed with a hooked extremity which passes under projecting extremities 40 on the pawls 28 and 38 and lifts them out of engagement with the teeth 27 to allow the spring 37 to snap the bar 32 back to its starting position.

35 The setting lever 23 and the internal gears are so timed that they line up the chosen characters on the type wheels 18 at a point where they will be struck by a cushioned platen 41. The platen 41 is carried on the upper extremity of a platen lever 42 hinged to the base at 43. The goods to be imprinted are laid across the platen 41 and held by the fingers of the operator with his thumbs bearing against thumb rests 44. The platen lever and the goods are forced forwardly 40 against the type wheels to give the desired impression.

45 The type at the impression point is inked in advance of the impression by means of an ink pad 45 which is carried in a rotatable pad holder 46 on the upper extremity of a hinged toggle lever. The toggle lever consists of an upper lever 47 and a lower lever 48, hinged together on a hinge pin 49 and constantly held in an extended position by means of a stop 56 and a tension spring 58. The hinge pin 49 is connected through the medium of a connecting rod 51 with the platen lever 42. The toggle lever carries, at each side of its upper extremity, a roller 52. The rollers 52 engage adjustable tracks 53 at the side 50 of the type wheels. The tracks 53 are mounted through the medium of slotted screw openings so that their positions can be adjusted to allow the pad 45 to contact the type with any desired pressure.

55 As before stated, the type is aligned by means

of the click members 36. However, to give additional assurance of alignment, an aligning wedge 54 is provided having a face extending across the entire series of type wheels and shaped to pass between the characters 18 thereon. This wedge is forced between the characters to lock the wheels immediately before they are engaged by the platen 41. This is accomplished by means of a compression spring 55 mounted on a spring rod 56. The spring rod is connected at its forward extremity with the toggle lever 41.

60 To clarify the description, let us follow a typical operation, assuming the goods are to be marked with the marking RHG. At the start the type wheels are all set at zero position by 15 means of the resetting lever 35. The operator now raises the setting lever 23 until its indicating pointer (see 57) comes opposite the letter "R". This causes the shaft 22 to rotate downwardly on its forward side and causes the key 24 to 20 engage the stop 54 of the first type wheel so as to rotate it upwardly at its forward edge until the "R" comes opposite the platen pad 41. He now drops the setting lever 23 to the bottom and then raises it to the "H" position. The 25 downward movement of the resetting lever causes the pawl 28 to contact the cam 29 which forces it to the right one tooth space so as to pull the bar 32 to the right and bring the key 24 within the second drive gear 21. The next 30 upward movement turns the second drive gear to bring its type wheel to the "H" position. Upon again returning the lever 23 to the starting position, the pawl 28 again engages the teeth 27 and pulls the key 24 into the third drive gear 21 35 which, in turn, turns its type wheel to the "G" position.

40 The goods to be marked are now laid across the platen 41 and pressed forwardly against the type wheels. The first forward movement causes the connecting rod 51 to swing the toggle lever 41 forwardly to press the ink pad 45 against the set-up characters R H G. Further movement causes the connecting rod to collapse the toggle lever, as shown in Fig. 2, causing the rollers 52 45 to ride downwardly on the tracks 53 to swing the ink pad away from the marking position and away from the type. The final movement presses the goods against the inked, set-up characters, imprinting the letters R H G thereon. After 50 all of the desired goods have been marked with the set characters, the operator pulls the resetting lever 35 to the broken line position of Fig. 2, causing its segment gear 34 to rotate the resetting bar 32 within the type wheels to engage the teeth 33 and cause them to return the three used type wheels to their original starting position.

55 It is desired to call particular attention to the mounting of the ink pad 45. The latter is 50 mounted in a rectangular holder, 46, which is pivoted along its longitudinal axis in a bracket 59 on the upper extremity of the toggle lever 41. A leaf spring 70 bears against the back of the pad holder and the latter is provided with a 55 finger knob 65 by means of which it may be quickly turned to the working position of Fig. 3 or the re-inking position of Fig. 4, the spring 70 acting to hold the pad in either desired position. This enables the pad to be readily inked without removal and without the use of tools.

60 The type wheels consist of annular members rotatably mounted about a cylindrical bearing sleeve 71 which serves as a housing for the gears 18, 20 and 21.

- The pawls 28 and 38 are mounted in a pawl housing 12 which is affixed to and rotates with the hollow shaft 22. The pawls are preferably similar in contour and both are pivoted on a pivot pin 73 in the pawl housing 12. The pawl 28 however, is provided with a slotted pin opening so that it may be moved longitudinally as well as hingedly. The pawl 38 is simply hinged on the pin 73. Two similar tension springs 74 hold the pawls in engagement with the bar teeth.
- The setting lever 23 is clamped to the gear segment 61 by means of a clamp screw 75 which passes through an accurate opening 76 in the arm to allow initial adjustment.
- While a specific form of the improvement has been described and illustrated herein, it is desired to be understood that the same may be varied, within the scope of the appended claims, without departing from the spirit of the invention.
- Having thus described the invention, what is claimed and desired to be secured by Letters Patent is:—
1. In a marking machine, a series of annular type wheels having internal gear teeth; a hollow sleeve serving as a bearing for said type wheels; an independent driven gear for each of said type wheels meshing with the internal teeth thereof; an independent drive gear meshing with each of said driven gears, all of said gears being located within said sleeve; and means for selectively rotating said drive gears.
  2. In a marking machine, a series of annular type wheels having internal gear teeth; a hollow sleeve serving as a bearing for said type wheels; an independent driven gear for each of said type wheels meshing with the internal teeth thereof; an independent drive gear meshing with each of said driven gears; a hollow shaft serving as a bearing for said drive gears; and a shiftable key on said hollow shaft for engaging said drive gears to successively secure them to said hollow shaft.
  3. In a marking machine, a series of annular type wheels having internal gear teeth; a hollow sleeve serving as a bearing for said type wheels; an independent driven gear for each of said type wheels meshing with the internal teeth thereof; an independent drive gear meshing with each of said driven gears; a hollow shaft serving as a bearing for said drive gears; a control rod longitudinally movable in said hollow shaft; a key projecting from said control rod through an axially extending slot in said hollow shaft so that as said control rod is moved longitudinally it will cause said key to successively engage said drive wheels.
  4. In a marking machine, a series of annular type wheels having internal gear teeth; a hollow sleeve serving as a bearing for said type wheels; an independent driven gear for each of said type wheels meshing with the internal teeth thereof; an independent drive gear meshing with each of said driven gears; a hollow shaft serving as a bearing for said drive gears; a control rod longitudinally movable in said hollow shaft; a key projecting from said control rod through an axially extending slot in said hollow shaft; ratchet teeth on said control rod; a pawl engaging said teeth; and means for actuating said pawl in consequence of the rotation of said hollow shaft to cause said key to successively engage said drive wheels.
  5. In a marking machine, a series of annular type wheels having internal gear teeth; a hollow sleeve serving as a bearing for said type wheels; an independent driven gear for each of said type wheels meshing with the internal teeth thereof; an independent drive gear meshing with each of
- said driven gears; a hollow shaft serving as a bearing for said drive gears; a control rod longitudinally movable in said hollow shaft; a key projecting from said control rod through an axially extending slot in said hollow shaft; ratchet teeth on said control rod; a pawl engaging said teeth; and a stationary cam positioned so as to be contacted by said pawl in consequence of the rotation of said hollow shaft so as to cause said control rod to successively engage said drive wheels.
6. In a marking machine, a series of annular type wheels having internal gear teeth; a hollow sleeve serving as a bearing for said type wheels; an independent driven gear for each of said type wheels meshing with the internal teeth thereof; an independent drive gear meshing with each of said driven gears; means for selectively rotating said drive gears, said internal teeth corresponding in number to the number of type characters on said type wheels; and a spring actuated click engaging the teeth of each of said driven gears for holding said type wheels in preset position.
7. In a marking machine; a series of annular type wheels having internal gear teeth; a hollow sleeve serving as a bearing for said type wheels; an independent driven gear for each of said type wheels meshing with the internal teeth thereof; an independent drive gear meshing with each of said driven gears; a hollow shaft serving as a bearing for said drive gears; a shiftable key on said hollow shaft for engaging said drive gears to successively secure them to said hollow shaft; a projecting member on each of said drive gears; a resetting arm journaled on said hollow shaft; and manually operated means for bringing said resetting arm into contact with said projecting members to return said type wheels to their initial position.
8. A marking machine comprising: a series of annular type wheels carrying marking characters; independent sets of operating gear within said series for each of said type wheels; a manually operated setting lever; an arcuate index for determining the position of said setting lever; and means for transmitting the successive movements of said setting lever to successive sets of operating gears so as to move said type wheels in succession to marking position.
9. In a marking machine, a series of annular type wheels having internal gear teeth; a hollow sleeve serving as a bearing for said type wheels; an independent driven gear for each of said type wheels meshing with the internal teeth thereof; an independent drive gear meshing with each of said driven gears; a hollow shaft serving as a bearing for said drive gears; a control rod longitudinally movable in said hollow shaft; a key projecting from said control rod through an axially extending slot in said hollow shaft; ratchet teeth on said control rod; a pawl engaging said teeth; means for actuating said pawl in consequence of the rotation of said hollow shaft to cause said key to successively engage said drive wheels; a spring urging said control rod against the action of said pawl; and means for lifting said pawl out of engagement with said ratchet teeth to allow said spring to return said operating rod to its initial position.
10. A marking machine comprising: a series of annular type wheels carrying marking characters; independent sets of operating gears within said series for each of said type wheels; a manually operated setting lever; an arcuate index for

- determining the position of said setting lever; means for transmitting the successive movements of said setting lever to successive sets of operating gears so as to move said type wheels in succession to marking position; means for inking the marking characters of said type wheels when the latter are at marking position; and means for pressing the goods to be marked against the inked characters.
- 5 11. A marking machine comprising a base; a series of annular type wheels supported above said base, said marking wheels carrying marking characters about their periphery; means for successively rotating said type wheels to bring selected characters into alignment at a marking position; a platen lever hinged to said base; a work platen carried by said platen lever opposite said marking position; an ink pad; a pair of hinged-together toggle levers hinged to said base at their lower extremity and supporting said ink pad at said marking position; a spring member maintaining said toggle levers extended; a connecting member extending from said platen lever 10 to the hinge point of said toggle levers so that the first movement of said platen lever will swing said ink pad against said type wheels at said marking position and further movement will collapse said toggle levers at their hinged-together point to withdraw said ink pad from said marking position; and stationary guide members for guiding said pad from said marking position as said toggle levers are collapsed.
- 15 12. A marking machine comprising a base; a series of annular type wheels supported above said base, said marking wheels carrying marking characters about their periphery; means for
- 20 13. In a marking machine of the class described having a control rod and key for successively engaging the gears of a series to a hollow shaft, means for shifting said control rod comprising: ratchet teeth on said control rod; a pawl contacting said teeth, said pawl being 25 mounted on said hollow shaft so as to rotate therewith and being longitudinally shiftable thereon; a stationary cam adjacent said shaft positioned to contact said cam as said shaft is rotated to cause said cam to shift said control 30 rod to bring said key into the next successive gear on said shaft; and means for rotating said hollow shaft.

WILLIAM S. PETTY.
